UNITED STATES PATENT OFFICE

WILLIAM G. CROTHERS, OF OAKFIELD, NEW YORK

FURNACE

Application filed November 29, 1927. Serial No. 236,560.

This invention relates to furnaces and more particularly to that type of furnace employing pulverized hydrocarbons as fuel.

An important object of the invention is to provide in a furnace of this character a novel and improved grate structure whereby all unburned particles of fuel are held in suspension in the furnace until they may be burned and burned particles are sifted gradually into an ash pit from which they may be removed from time to time.

A further object of the invention is to provide a grate construction, such that the furnace may be readily relieved of such particles as will not pass through the sifter grate.

These and other objects I attain by the construction shown in the accompanying drawings, wherein for the purpose of illustration is shown a preferred embodiment of my invention and wherein:

Figure 1 is a vertical sectional view through the lower end of a furnace constructed in accordance with my invention;

Figure 2 is a sectional view taken on the horizontal planes indicated by the line 2—2 of Figure 1;

Figure 3 is a sectional view taken on the vertical plane indicated on the line 3—3 of Figure 1;

Figure 4 is an elevational view of a portion of one of the end twyers, the support therefor and the grate bars associated therewith;

Figure 5 is an elevational view illustrating the manner in which the clinker door is supported against tilting movement in one direction;

Figure 6 is a sectional view taken on the vertical plane indicated by line 6—6 of Figure 5;

Figure 7 is a sectional view taken on the vertical plane indicated by line 7—7 of Figure 1;

Figure 8 is a sectional view taken on the horizontal plane indicated by line 8—8 of Figure 1;

Figure 9 is a sectional view taken on the horizontal plane indicated by line 9—9 of Figure 1;

Figure 10 is a top plan view of one of the fuel jets of the furnace; and

Figure 11 is a view in end elevation of the jet.

Referring now more particularly to the drawings, the numeral 10 generally designates the furnace wall and 11 an inclined baffle of fire brick or similar substance defining an inwardly extending rim forming a portion of the lower wall of the fire box, which wall is suitably supported, as indicated at 12, and the supports for the inner edge of the wall likewise provide supports for twyers 13 and 14. The twyers 13 and 14 each comprise a rectangular tube coextensive with the sides of the opening with which they are associated. The twyers 13 and 14 are provided at their inner lower corners with openings 15. The passage of air through the openings 15 is in each instance controlled by a gate 22 carried by a rockably mounted shaft 23 controllable to move the gate from open to closed position. The twyers 13 which are arranged along the ends of the opening are further provided at their inner upper corners with openings 20, these openings being controlled by a gate 18 carried by a rockably mounted shaft 19. Any suitable means, not shown, may be provided for rocking the shafts 23 and 19 to effect the closing or opening of the gates 22 and 18. Any suitable means may be provided for supplying air under pressure to said twyers. In the present instance, the twyers are illustrated as interconnected and as having one thereof in communication with a pipe 24 leading from a blower (not herein shown).

The numeral 25 generally designates tracks arranged beneath the ends of the opening defined by the wall 11 over which operate roller supported carriages 26 which, through cross bars 27, support a sifting grate, generally designated at 28. This grate has its upper face slightly spaced from the lower faces of the twyers and each twyer 13 and 14 is provided with a plurality of depending ears 29 between which are extended the ends of grate bars 30, which are held to the ears by pivots 31 extending through both thereof. The inner ends of these bars are threaded upon longitudinally extending rods 32, spacers or bosses 33 maintaining the bars in

slightly spaced relation, so as to provide an air passage therebetween. The inner ends of these bars rest upon the upper surface of the sifter grate 28 and the bars thus serve 5 to seal the space between the twyers and this grate.

The sifter grate 28 has a central opening which is closed by a clinker door 35 pivotally supported by a shaft 35^a, and supported 10 against rocking movement in one direction by lugs 34 carried at one side of the opening by the relatively fixed or non-rocking portion of the grate. An operating rod 36 for this door is connected to an arm 36^a extending 15 downwardly from the shaft 35^a and is extended through an opening formed in a furnace wall 10 and operates over a roller 37. The outer end of this rod has formed therein 20 a series of notches 38 for engagement by a lever 39. The lever 39 is oscillatable in the general direction of the bar 36 and is also oscillatable in a plane transverse to this bar, its movement being controlled by a slot 40 in a control platform 41 through which it extends. 25 When disposed in the slot 40, the lever engages one or the other of the notches 38 and is only shiftable longitudinally of the bar 36. The slot 40 has, however, a cove 42 into which the lever may be moved to disengage the same 30 from the rod.

Within the furnace is arranged a slowly rotating shaft 43 having cranks 44 link-connected, as at 45, with the grate 28, so that this grate is reciprocated as the shaft is rotated. It will be obvious that with the lever 39 in the cove 42, the reciprocation of the rod 36 resulting from the reciprocation of the grate, is not interfered with. The rotation of the shaft 43 may be discontinued at any desired time by manipulation of a clutch 46 by an operating rod 46^a therefor.

Pulverized fuel is fed to the furnace by conduits, which enter the furnace through one wall thereof and adjacent opposite sides 45 thereof. Only one of said conduits is shown and designated 56. The numeral 57 generally designates a conduit leading from a blower which, if desired, may be the same blower which supplies the pipe 24. This 50 conduit 57 has two outlet branches entering the furnace through the walls thereof below the fuel inlets 56. One only of the outlets is shown and designated 59. These outlets have their terminals flattened, as indicated at 55 60, so that they provide a broad relatively high speed jet across which the fuel from the conduits 56 would fall. These jets cause the fuel to be blown out into the furnace and thoroughly intermingled with the air from the nozzles, so that it may be readily ignited. The burning fuel falling downwardly through the furnace will be consumed or nearly so. Unconsumed particles coming in 65 the range of the air blast from the openings 20 of the twyers 13 are blown back into the

furnace, so that they may finish burning. Particles falling on the grates are blown therefrom by the air blasts from the openings 15 of the twyers 13 and 14, so that they may be sifted to remove all ash therefrom. As 70 the larger particles or clinkers collect, they may be removed at any time by disengaging the clutch 46, engaging the lever 39 with the rod 36 and tilting the door or clean-out section 35.

Since the construction hereinbefore set forth is capable of a certain range of change and modification without materially departing from the spirit of the invention, I do not limit myself to such specific structure except 80 as hereinafter claimed.

I claim:—

1. In a furnace, a wall, a baffle inclining inwardly and downwardly from the wall and at its inner edges defining a central opening, 85 a grate reciprocably mounted beneath said opening and having a central clean-out opening, a door controlling the clean-out opening, means for reciprocating the grate, a shaft rockably supporting the door on the grate, 90 an arm carried by the shaft, a rod connected with the arm and a lever swingable in a plane transversely of the rod to engage or disengage the same from the rod and in a plane longitudinal to the rod when engaged 95 therewith to shift the rod to operate the door.

2. In a furnace, a wall, a baffle inclining inwardly and downwardly from the wall and at its inner edges defining a central opening, 100 a grate beneath said opening, twyers arranged between the lower edges of the baffle wall and said grate, said twyers having openings for directing a blast of air upwardly and inwardly therefrom, and means for blowing powdered fuel into the furnace at the upper end thereof.

3. In a furnace, a wall, a baffle inclining inwardly and downwardly from the wall and at its inner edges defining a central opening, 110 a grate beneath said opening, and twyers arranged between the lower edges of the baffle wall and said grate, said twyers having openings for directing a blast of air upwardly and inwardly therefrom, and certain of the twyers having other openings directing a blast of air across the grate.

4. In a furnace for burning pulverized fuel, a furnace wall, a baffle inclining inwardly and downwardly from the wall and at its inner edges defining a central opening, twyers arranged about the edges of the opening beneath the inner edges of the wall, a grate reciprocably mounted beneath and in spaced relation to the twyers, means for reciprocating said grate, and bars pivotally connected with the twyers at their upper outer ends and resting upon the grate at their inner lower ends and constituting a grate connection therebetween.

5. In a furnace for burning pulverized fuel, a furnace wall, a baffle inclining inwardly and downwardly from the wall and at its inner edges defining a central opening, twy-
ers arranged about the edges of the opening
5 beneath the inner edges of the wall, a grate reciprocably mounted beneath and in spaced relation to the twy-ers, means for reciprocating said grate, bars pivotally connected with the twy-ers at their upper outer ends and resting upon the grate at their inner lower ends and constituting a grate connection therebetween, a shaft to which the inner lower ends of the bars at each side of the opening
10 are connected and means holding the ends of the bars in spaced relation to one another.

15 6. In a furnace, a wall, a baffle inclining inwardly and downwardly from the wall and at its inner edges defining a central opening, a grate mounted beneath said opening and in spaced relation to the baffle, twy-ers arranged beneath the edges of the opening and having openings for delivering air through the opening at an angle inclining inwardly and upwardly above the center of the opening, dampers within the twy-ers for controlling the passage of air through said openings, said twy-ers having other openings directing air downwardly in the direction of and longitudinally of the grate and dampers within the twy-ers for controlling the last named openings.

In testimony whereof I hereunto affix my signature.

35 WILLIAM G. CROTHERS.
